SHOE MACHINE FRAME

Alfred R. Morrill, deceased, late of Woodstock, Vt., by Ruth W. Morrill, administratrix, Woodstock, Vt., assignor to United Shoe Machinery Corporation, Flemington, N. J., a corporation of New Jersey

Application May 10, 1949, Serial No. 92,407

10 Claims. (Cl. 112—258)

1

The present invention relates to improvements in supporting frames for heavily constructed machines and more particularly to frames for machines of the type employed in high-speed shoe sewing, which frames frequently have arrangements for heightwise adjustments. A machine of this type embodying the features of the present invention is illustrated and described in the present inventor's copending application for United States Letters Patent Serial No. 706,219, filed October 28, 1946, for Shoe Sewing Machines (now Patent No. 2,502,629, granted April 4, 1950), of which application the present application is a division.

One object of the invention is to enable the use of an especially rugged light weight and inexpensive construction and arrangement of parts in a fabricated supporting frame of a sewing machine. Another object of the invention is to provide a fabricated frame for a sewing or other machine of similar nature in which a structure having both thin relatively flexible sheet metal and heavy rigid castings are employed to contribute their characteristics to each other with the result that breakage is far less likely to occur than heretofore during shipment.

In a machine frame disclosed in an application for United States Letters Patent, No. 606,895, filed July 25, 1945, in the name of Frederick A. Prahl, Jr. (now Patent No. 2,544,723, granted March 13, 1951), a fabricated construction of open box-like form with C-shaped cross-section provides yielding resilient action to absorb shocks imparted to a rigid base member in the frame and reduces breakage of the frame and base or injury to the operating parts of the machine during transportation. Such frame is effective where comparatively lightweight machines are to be supported. For the support of heavier machines, particularly when the frame and machine are assembled for transportation from one place to another as a unit, the frame of the application referred to may have excessive yielding action under rough handling. Furthermore, the frame of the Prahl application is arranged for convenient height adjustment and is provided with a motor support separately mounted upon the frame. When the frame is raised and lowered, therefore, the motor support is not similarly raised and lowered so that if a driving belt is employed to connect the machine, the belt will be thrown out of adjustment when the frame height is changed. As a result a separate height adjustment for the motor support must be made.

More particularly an object of the present

invention is to provide such frame structure with improved means of adjustment to enable the height of the machine to be suited readily to the requirements of the operator. A still further object is to improve and render more effective the frame of the Prahl application, above identified.

Accordingly, a feature of the present invention relates to an improved fabricated frame for a shoe sewing or similar machine head having a rigid base, ordinarily composed of cast iron, a hollow yielding column of relatively light weight flexible sheet metal resiliently mounted on the base, a rigid post within the column of substantially smaller dimensions than the column to provide vacant space about the post and a bearing sleeve secured to the upper portion of the column for releasably clamping the post to provide easy vertical adjustment, in which a second bearing sleeve is secured to the base for receiving the lower end of the post to limit the yielding action of the column. Preferably, a motor support is secured to the post between the two bearing sleeves within the column to enable movement of the post and machine head while maintaining a uniform distance between the motor support and the head. By this construction no separate adjustment is necessary to insure proper tightness of the driving belt. The motor support being carried by the post, a rigid construction is provided not affected by the yielding action of the sheet metal column between the base and the sewing head. In one form of this feature the driving belt passes about a variable speed pulley and means inside the column is arranged for shifting the motor support along the rigid post to vary the driving ratio of the pulley in tightening or loosening the belt. As hereinafter described, use is made of the space within the column to house a jack screw for raising or lowering the machine supporting post in addition to the post clamping means.

These and other features of the invention as hereinafter described and claimed will become apparent from the following detailed specification and accompanying drawings, in which

Fig. 1 is a view in front elevation of a machine embodying the invention;

Fig. 2 is a view in right side elevation of the machine of Fig. 1;

Fig. 3 is a side sectional view on an enlarged scale of the supporting column for the machine looking from the right;

Fig. 4 is a horizontal section of the supporting column and base of the machine as viewed along the line IV—IV of Fig. 3; and

Fig. 5 is another similar section as viewed along the line V—V of Fig. 3.

The machine illustrated in the drawings is a stitch-down thread lasting machine arranged for operation upon an unchanneled extension sole and an overlapping marginal portion of an upper mounted on a last, a through-and-through seam being inserted in the parts. The sewing head of the machine is indicated at 10 and is supported upon a rigid cast metal floor mounting member 12 forming a base within which is fulcrumed a control treadle 14 projecting from the front of the machine. The structure for supporting the sewing head on the base is particularly advantageous for the purpose intended and presents a comparatively smooth, unbroken external contour while at the same time enabling easy and effective height adjustment of the machine without the use of especially constructed expensive parts, the assembly of which is difficult or inconvenient. The structure is fabricated to combine in a particularly desirable manner the best qualities of castings and enclosing sheet metal of substantial flexibility and resiliency while maintaining an arrangement providing lightness together with maximum rigidity.

According to the invention a construction is employed which is an improvement over that disclosed in the Prahl application providing effective shock absorption while limiting the yielding torsional action within practical limits. The improved construction not only provides practical limits to the yielding action but also enables the use of a motor support arrangement of a particularly desirable form. The driving connections of the machine also are enclosed by the structure, thus guarding against accidental contact with moving machine parts and obviating the necessity of separate guard members.

Referring more particularly to the drawings, the frame of the structure has a resilient shock absorbing column 16, similar to the column of the Prahl application, connecting the base member 12 with a machine head supporting member so arranged as to limit the yielding action of the column on the base.

The column 16 supports the weight and encloses many of the devices and moving parts of the machine. It comprises a single plate bent into rectangular form with smoothly rounded corners and spaced vertical edges at the rearward side, giving a cross sectional shape resembling generally the letter C. The sheet metal plate of the hollow column has good weight supporting characteristics but for torsional resistance along its heightwise axis, particularly in resisting strains set up during shipment of the machine, reinforcement of the column is desirable.

For the purpose of accentuating the yielding action, a resilient mounting at the upper end of the column consists of a flanged plate 18 (see Figs. 3 and 5) to which is secured by bolts or machine screws 20 at location spaced inwardly of the flanges on the plate a vertical cylindrical cast metal bearing sleeve 22. To mount the column resiliently on the base, the lower end of the column has secured to it the flanges of a plate 23 bolted at 25 at similarly inwardly spaced positions, best shown in Fig. 4. The sleeve is substantially smaller internally than the internal cross-sectional area of the column and is arranged vertically nearer to the front edge of the plate 18. Within the sleeve is disposed a hollow rigid post 24 fitting the sleeve for vertical sliding

movement and having at its upper end the machine support to be described.

If the supporting column 16 is constructed of sheet metal having a light gage the flexibility of the column, due to its manner of resilient mounting on the base, may be excessive, particularly during shipment of the machine. As a result the torsional action on the column may be carried beyond the elastic limit with the result that the column will be distorted permanently. To avoid excessive torsional action and swaying movement of the column beyond the elastic limit, in the embodiment of one feature of the invention, the rigid post 24 is made longer than the corresponding post in the frame of the Prahl application, reaching nearly to the bottom of the base 12 and passing loosely through a second bearing sleeve 26 formed integrally with the base 12. The hollow post 24 forms a backbone for the supporting structure of the frame not only to give the structure torsional strength but also to hold the column from swaying movement on the base beyond practical limits.

To secure the post 24 adjustably in fixed position in the sleeve 22, the rearward side of the post is slotted at 28 (see Fig. 4), and a downwardly extending rim of the sleeve 22 carries a clamping bolt 30 having its head inside the post and its shank passing through the slot 28. By tightening the nut on the clamp bolt 30, the post is secured against vertical movement in the sleeve. For use while the machine is being shipped from one factory to another, means similar to the bolt 30 may be employed to clamp the sleeve 26 in the base to the post 24.

To adjust the height of the machine vertically, the clamping means including the bolt 30 is loosened and a vertically arranged jack screw 32 is rotated. The jack screw 32 is threaded received within the bearing sleeve 22 and engages at its upper end a support or flange 34 for a sewing head mounting at the upper end of the post 24. The lower end of the jack screw 32 is squared to receive a wrench and is accessible together with the nut on the clamp bolt 30 through the opening provided between the spaced vertical edges of the column 16.

For actuating the machine a driving motor 36 is provided. The motor is mounted on the post 24 which carries along its central portion between the bearing sleeves 22 and 26 a second support in the form of a bracket 38 within the column having a sleeve portion surrounding the post and a rearwardly extending portion to which is clamped a motor support bracket 40. The rearwardly extending portion of the bracket 38 and the motor support bracket 40 together form a projection passing outside the column between its vertical edges in a manner to form a particularly rugged construction with the full weight of the operating parts both in the machine head and the driving motor bracket supported by the post 24. The entire weight of the operating parts in the machine is borne in turn by the sheet metal column 16 in the form of compression only, the lateral strains applied to the column, which is of relatively thin gage, being limited by the restraint offered by the post in the bearing sleeve 26.

A further feature of the invention relating to the supporting structure for the driving motor 36 provides a quick acting speed adjustment of a driving belt 42 between the motor and the sewing head of the machine, both said adjustment parts and the driving connections being

enclosed by the column. For this purpose, the motor has a pulley 44 (Fig. 2) which is of the variable-speed type in which two opposed conical flanges are pressed yieldingly together against the inclined sides of the belt 42 having the usual V-section. This pulley, accordingly, yields under the tension of the belt to cause separation of the flanges and the belt moves inwardly toward the central axis of the pulley as the belt is tightened, thus reducing the effective diameter of the pulley and reducing the speed of the sewing shaft accordingly. When the belt is loosened, the opposite action takes place, the belt moving outwardly along the conical flanges of the pulley 44.

To tighten or loosen the belt 42 and thus to change the speed of a main sewing shaft 46 (see Fig. 2) in the head of the machine, the bracket 38 is slidably mounted on the post 24 and adjustable means is connected between the post and the bracket. To slide the bracket on the post the bracket receives a vertical threaded rod 48, the upper end of which has an enlarged lug through which passes a pin 50 secured diametrically to the post 24. The threaded rod 48 is surrounded at its lower end with an internally threaded helical gear 52 disposed within a side opening of the bracket 38. Meshing with the teeth on the gear 52 is a corresponding gear 54 of somewhat smaller diameter secured on a horizontal adjusting shaft 56 rotatable in bearings formed by the bracket 38 and arranged to project through vertical slots in the post and a corresponding slot 58 in the forward side of the column 16. On the forward end of the adjusting shaft 56 is a hand wheel 60, rotation of which causes the helical gear 54 to rotate and raise or lower the bracket 38 on the post 24, increasing or reducing the distance between the bracket and the head support 34. Movement of the bracket on the post tightens or loosens the belt 42 in the desired manner without changing the over-all height of the machine. Due to the arrangement of the motor support bracket on the post, height-adjusting movement of the post to raise and lower the sewing head of the machine does not change the sewing speed of the machine or affect the driving belt in any way.

To impart a finished and pleasing appearance to the machine-supporting structure, the support flange 34 has secured to its under surface a two-part apron 62 provided with downwardly extending sides fitting closely with the outer surfaces of the column 16. When the height of the machine on the column is changed, the apron 62 moves with the sewing head but the downwardly extending sides of the apron are of sufficient length to overlap the column in all positions of the sewing head.

The machine is equipped with a high-speed driving and a low-speed reverse stopping mechanism of compact and relatively simple design arranged conveniently for bringing the machine to rest with the stitch-forming devices in a predetermined relationship free of the work, and with the shoe-clamping members released from the shoe so that a new shoe may readily be substituted for a sewn one. The driving and stopping mechanism has high and low-speed driving clutches, the low-speed driving clutch acting, first, as a brake after the high-speed clutch has been disengaged and, finally, after reversing the rotation, bringing the machine to rest in the desired predetermined position.

The driving and stopping mechanism of the

machine is more fully disclosed in the applicant's prior application and is generally similar to that disclosed in United States Letters Patent No. 1,099,326, granted June 9, 1914, upon an application filed in the name of Laurence E. Topham.

To control the driving and stopping mechanism the head of the machine has a downwardly extending arm of a lever 64 (Fig. 3) formed with a projection entering a notch in an arm of a treadle-actuated bell-crank lever 66 having a pivot 68 formed integrally with the lever and rotatable in a bearing in the head of the machine. The arrangement is such that the head of the machine may readily be removed from the flange 34 and the treadle-actuated lever 66 will separate from the control lever 64 without dismantling any of the other treadle connections. The treadle lever has a horizontal arm connected to the upper end of a downwardly extending rod 70 secured at its lower end to a clamp 72 surrounding the rod 70 and a similar rod 73 connected at its lower end to the treadle 14. The treadle 14 projects from the front of the machine base and is pivotally mounted on a shaft 74 at the rear of the base. By these connections, the machine may be driven and the speed controlled in the usual way by increasing or decreasing the pressure exerted on the treadle 14. Upon release 30 of the treadle, the treadle rods are raised by a spring 76 contained wholly within the base and the control lever 64 is rocked in a direction to throw out of operation a high-speed clutch and set in operation the stopping mechanism.

While the illustrated frame structure is of particular advantage for use with a sewing or other shoe machine in which it is desired to adjust the height to accommodate the convenience of the operator of the machine, certain features of the structure are useful where no height adjustment is required. Also certain features of the invention may be employed with beneficial results with machines other than sewing or shoe machines, a simple easily adaptable arrangement having been provided for controlling similar machines.

The nature and scope of the invention having been indicated and a specific embodiment having been described, what is claimed is:

1. A fabricated frame for a machine of the type described, having a rigid base, a hollow column of relatively flexible sheet metal resiliently mounted on the base, a rigid post within the column of substantially smaller size than the internal cross-sectional area of said column to provide vacant space about the post in the column, and a bearing sleeve resiliently mounted on the upper portion of the column fitting the post to enable sliding movement of the post in the sleeve, in combination with means for releasably clamping the post to the sleeve disposed wholly within the space in the column to eliminate external appendages on said column, and a second bearing sleeve secured to the base for receiving the lower end of the post which passes loosely through it to limit the yielding action of the column on the base.

2. A fabricated frame for a machine of the type described, having a rigid base, a hollow vertical column secured to said base, a rigid post within the column of substantially small size than the internal cross-sectional area of the column, a bearing sleeve secured to the upper portion of said column fitting said post, a support for a machine head carried by said post, and

a second bearing sleeve in axial alignment with the sleeve on the column secured to said base, in combination with a motor support on said post between the two bearing sleeves within the column to enable movement of the machine head while maintaining a uniform distance between the motor support and the head.

3. A fabricated frame for a machine of the type described, having a rigid base of cast metal, a hollow vertical column of relatively flexible sheet-metal plate bent into a generally C-shaped cross-sectional form resiliently mounted on said base with spaced vertical edges at one side, a rigid post within the column of substantially smaller size than the internal cross-sectional area of the column, a rigid vertical bearing sleeve resiliently mounted on the upper portion of said column fitting said post, and a support for a machine head carried by said post, in combination with a motor support on said post spaced along the post from the sleeve with a portion for supporting the motor projecting from between the spaced vertical edges of the sheet-metal column.

4. A fabricated frame for a machine of the type described, having a base, a hollow vertical column of sheet metal secured to said base, a rigid post within the column, a bearing sleeve for said post secured to the upper portion of said column, and a machine head support carried by said post outside the column, in combination with a second support on the post inside the column, said second support being spaced from the machine support along the post and projecting from the column between the bearing sleeve and the base, a motor on said second support, a variable-speed driving pulley having conical flanges yieldingly pressed together on the motor, a belt surrounding the pulley and extending to the machine head, and means inside the column for shifting the motor support along the post in a direction lengthwise of the belt to vary the driving ratio of the pulley and the belt as the belt is tightened or loosened by the shifting movement of the motor support.

5. A fabricated frame for a machine of the type described, comprising a cast base, a hollow column of relatively flexible sheet metal plate bent into rectangular C-shaped cross-sectional form with spaced edges at one side, a bearing sleeve secured to the upper portion of said column, a rigid post of substantially smaller size than the internal cross-sectional area of the column slideable vertically in said bearing sleeve within the column, a machine head support carried by said post, and means for securing said post in any position of heightwise adjustment in said sleeve, in combination with a jack screw within the column threadedly received in the bearing sleeve and engaged at its upper end with the support on the post for moving the post vertically to raise and lower the machine head.

6. A fabricated frame for a machine of the type described, having a rigid base of cast metal, a hollow vertical column of relatively flexible sheet-metal plate bent into a generally C-shaped cross-sectional form mounted on said base with spaced vertical edges at one side, a rigid post within the column of substantially smaller size than the internal cross-sectional area of the column, a rigid vertical bearing sleeve secured to the upper portion of said column fitting said post, and a machine head support carried by said post, in combination with a motor support mounted on said post, said motor support being

spaced along the post from the machine support and projecting from between the spaced vertical edges of the sheet-metal column, and means within the column between the column and the post for adjusting the motor support along the post to increase or decrease the distance between the machine head and the motor support.

7. A fabricated frame for a machine of the type described, having a rigid base of cast metal, a hollow vertical column of relatively flexible sheet-metal plate bent into a generally C-shaped cross-sectional form mounted on said base with spaced vertical edges at one side, a rigid post within the column of substantially smaller size than the internal cross-sectional area of the column, a rigid vertical bearing sleeve secured to the upper portion of said column fitting said post, and a machine head support carried by said post, in combination with a motor support slidingly mounted on said post, said motor support being spaced along the column from the machine support and projecting from between the spaced vertical edges of the sheet-metal column, and means within the column mounted between the column and the post and operatively connected between the post and the motor support for adjusting the motor support along the post to increase or decrease the distance between the machine head and the motor support, comprising a hand wheel projecting outside the column.

8. A fabricated frame for a machine of the type described, having a base, a hollow vertical column of sheet metal secured to said base, a rigid post within the column, a bearing sleeve for said post secured to the upper portion of said column, and a support for a machine head carried by said post, in combination with a second support on the post inside the column between the column and the post extending outside the column, a motor outside the column on said second support, a pulley on the motor projecting into the column and a belt surrounding the motor pulley within the column for driving said machine.

9. A fabricated frame for a machine of the class described, having a base, a hollow column in the base, a post within the column, a bearing sleeve for said post secured to the upper portion of said column, and a support for a machine head carried by said post, in combination with a motor support mounted on said post, a threaded shaft within the column connecting the motor support and post, a nut on said shaft rotatable to move the motor support along the post, and a hand wheel projecting from one side of the column geared to the nut on said shaft for conveniently shifting the motor support along the post to change the distance between the motor support and the head support without changing the height of the machine on the column.

10. A fabricated frame for a machine of the type described comprising a cast base, a hollow column of relatively flexible sheet metal plate bent into a C-shaped cross-sectional form with an opening at the rear, a bearing sleeve secured to the upper portion of the column, a rigid post of substantially smaller size than the internal cross-sectional area of the column slideable vertically in the bearing sleeve while providing substantial vacant space within the column, a machine head support carried by the post, and means for securing said post in any position of heightwise adjustment in said sleeve, in combination with a motor support slidingly mounted on

the post in spaced relation to the machine support, said motor support passing rearwardly from the post and outside the column between its spaced vertical edges, and adjusting means operatively connected between the post and the motor support including a hand wheel shaft projecting forwardly from the forward side of the column acting when rotated to slide the motor support along the post.
